UNITED STATES PATENT OFFICE.

LOUISE H. BOCH, OF CHICAGO, ILLINOIS.

FOLDABLE GARMENT-PROTECTOR.

1,218,831.

Specification of Letters Patent. Patented Mar. 13, 1917.

Application filed October 8, 1915. Serial No. 54,718.

To all whom it may concern:

Be it known that I, LOUISE H. BOCH, a citizen of the United States, and resident of Chicago, in the county of Cook, State of Illinois, have invented certain new and useful Improvements in Foldable Garment-Protectors, of which the following is a specification.

My invention relates to means for protecting articles of clothing and the like, and has for its purpose to provide a receptacle of that character wherein many garments may easily be inserted and suspended, and which will effectually protect the contained garments against the deposit of dust and exterior contact.

Another object is to provide an adjustable protector which can be adapted for use in closets of varying size. A principal feature of my invention is a simple and efficient means for supporting the protector and its contents as a whole, this support or suspension device being preferably in the form of a light wire frame the suspension elements or arms being disposed in the plane of the garment supports or above the center of the protector thus carrying the weight in an efficient manner without employing an expensive or heavy frame.

Further objects of my invention are to provide an article which will be convenient in use, easily adjusted and capable of being folded, rolled or collapsed for transportation or storage or which can be hung or placed in a trunk with the garments inclosed therein.

With these and other objects in view the invention consists in certain novel details of construction and combination of parts more fully hereinafter disclosed and particularly pointed out in the claims.

The drawing is a perspective view in which 5 designates the bag or body portion of the protector which may be any flexible material and of any desired dimensions and preferably having the top 6 and bottom 7 closed. In the preferred form shown I provide for entrance to the interior a slit in the front face of the bag. To guard against the admission of dust and the like, I form a double flap 8 in the edge of the bag forming one side of the slit, the flap 8 being of greater width to extend over and embrace the edge 9 of the other side of the slit.

For supporting the bag and for providing suspension means for the garments, I employ a frame of two parts, a substantially U-

shaped vertical or suspending portion 10 and a substantially rectangular body member 11 pivotally or hingedly connected by loops 12 in member 10 or other well known means, 60 thus permitting the member 11 to be swung into the plane of member 10 and then allow folding or rolling of the bag about the support. The upstanding members 13 of the member 10 are provided with hooks 14 at 65 their ends, and the hanger joining them is composed of two parts slidably joined as at 15.

The member 11 may be formed of one piece, but I prefer to form it of several 70 pieces joined together in the manner shown so as to permit ease of folding, and the longer members formed of two pieces slidably joined as at 16. The width of the member 11 is made sufficient to permit the insertion of a hanger in the bag transversely thus accommodating a large number of garments and affording easy withdrawal and replacement thereof. By making the longer portions of the members 10 and 11 slidable, I 80 provide a support which may be inserted in bags of different widths or which may be extended or shortened to adapt the device for use in closets or spaces of different widths.

The bag may be provided with apertures 85 17 in the top 6 for the reception of arms 13. If desired the connections through the loops 12 may permit the movement of the member 11 to substantially overlie the member 10 thus making the support more 90 compact for transportation. It will be noted that these arms are disposed midway between the front and rear walls of the bag and in the vertical plane of the hanger supporting bar or in other words at the center 95 of the load. This arrangement permits of the use of a very light and inexpensive frame. I am aware that protectors have been made with bags having a rigid supporting and distending frame but the supports have been placed at one side of the center of the weight or load and have necessarily been made heavy and expensive. My device is not only cheap and light but it is more efficient than a bracket form of support and at the same time permits the bag to be held distended and prevents pressure on the garments inclosed thereby.

By providing two suspending arms 13 with hooks 14 and disposing them at the ends of the frame, I prevent displacement 110 of the bag or its contents when garments

are not hung exactly in the middle of the hanger bar, which makes the use thereof much easier. The form of the support distends the bag in its upper portion thus affording a free space of the full cross-sectional area of the bag thereby facilitating the placing and removal of the garments and preventing any wrinkling thereof by pressure from the sides of the bag.

10 I claim:

1. A foldable garment protector comprising a cover of flexible material, a supporting frame for said cover, said frame being adapted to support the upper end of said cover distended, and said frame being composed of a telescopic body member, a suspending member pivotally connected to said body member, said supporting member being also telescopically formed and forming the garment suspending member, substantially as described.

2. In a device of the class described, the combination of a cover of flexible material and a frame, said frame comprising a normally horizontally disposed extensible body member, a supporting member pivotally and slidably connected to the body mem-

ber, also telescopically formed and being adapted for co-active extension movement therewith, said cover being adapted to hang from said frame and provided with a centrally-disposed aperture, said supporting member forming the garment suspending member, substantially as described.

3. A foldable garment protector, comprising a cover of flexible material and a collapsible supporting frame for said cover, the frame consisting of an extensible body member, and an extensible suspending member, said suspension member being pivotally connected to said body member, the suspending means having a pair of hook arms for attachment to a wall, a hanger bar formed by bending the hook arms at 90 degrees and telescopically joining the bent portions, and said cover having a centrally-disposed opening therein, substantially as described.

Signed at Chicago, Illinois, this 4th day of October, 1915.

LOUISE H. BOCH.
